UNITED STATES PATENT OFFICE

THOMAS E. GJORUP, OF CHICAGO, ILLINOIS, ASSIGNOR OF ONE-THIRD TO FRANK C. VOISINET, OF CHICAGO, ILLINOIS

ENVELOPE

Application filed January 14, 1928, Serial No. 81,277. Renewed September 30, 1929.

My invention relates to improvements in envelopes and the like, and it consists in the combinations, constructions and arrangements herein described and claimed.

5 An object of my invention is to provide an envelope which does not require moistening in order to effectually seal it, thereby obviating the necessity of moistening the adhesive as is ordinarily done by means of the 10 tongue with envelopes in common use.

A further object of my invention is to provide an envelope in which means is provided for showing at once any attempt to open the envelope.

15 A further object of my invention is to provide an envelope or container having an adhesive which is in condition for immediately sealing the envelope without the use of water, but which will not be devoured by 20 insects, especially those found in tropical countries which do devour gum, mucilage and glue.

Other objects and advantages will appear in the following specification, and the novel 25 features of the invention will be particularly pointed out in the appended claim.

My invention is illustrated in the accompanying drawings, forming part of this application, in which

30 Figure 1 is a rear view of an envelope with the adhesive applied thereto,

Figure 2 is a view of a portion of an envelope after it has been opened and resealed, and

35 Figure 3 is a view of a blank for making a box and having adhesive applied thereto which does not require water for effective sealing of the parts of the box.

40 In carrying out my invention, I may make use of a blank for forming an envelope of the ordinary shape. Thus in Figure 1, A is the main body portion, and B, C and D are the flaps which are integral therewith, 45 and which, when folded, form the main con-

tainer. The flap E, when sealed, completes the envelope.

On the edge of the flap E, I dispose a sealing material F. This material is preferably some adhesive which does not require 50 moistening, such as a rubber solution. Thus a solution of rubber in chloroform or benzol is well adapted for the purpose.

A similar coating G is applied to the back of the envelope so that when the flap is 55 folded over, the coatings F and G will register. I have found that if the paper has a smooth surface, the adhesive will adhere better by roughening the paper before the adhesive is applied. An envelope thus applied with adhesive of the type described does not have to be moistened, because it is only necessary to press the flap against the back portion of the envelope to cause the 60 two coatings F and G to adhere and to make a firm seal for the envelope. This obviates the necessity of moistening the gummed surface as is ordinarily done, and does away 65 with the unsanitary method of licking the envelope.

70 In Figure 3, I have shown a modified form, which, in this instance, is a blank for use in making boxes. Obviously, the adhesive material might be applied to blanks of other shape than that shown for making 75 boxes without departing from the spirit of the invention. In the present instance, the body portion H of the box has the flaps K, R, M and P. The flaps R and P have auxiliary portions r. The ends of the flaps K and M are coated with the adhesive on one 80 side, while the portions r are coated with solution on the opposite side. The boxes, or rather the blanks from which they are made, are shipped to the consumer flat, and 85 in order to prevent the sticking of the adhesive, I may make use of sheets of paraffin paper or the like.

In making the box, all that is necessary 90 is to bend up the sides M and K, R and P,

and bring the end portions *r*, which have been treated with the adhesive on one side, into engagement with the adhesive covered ends of the portions *M* and *K*, thus causing the sides to adhere so as to complete the body portion of the box. In this form of the device, as well as the envelope, no moisture is required for effecting the firm sealing of the parts.

10 In the case of the envelope, I have provided means whereby any attempt at opening the envelope and resealing it will be detected. This consists in impressing either before or after applying the adhesive a 15 sign or trade mark, such as that shown at *W* in Figure 1. This may be either upon the flap or upon the parts to which the flap is to be sealed. Owing to the fact that the envelope cannot be opened by steaming it, 20 any opening of the envelope by an unauthorized person who wishes to escape detection, must be by pulling outwardly on the flap *E*. Even should he succeed in separating the parts without tearing them, a portion 25 of the design will be broken; that is to say, part of it may remain intact on the flap, while the other part will adhere firmly to the coating *G* and the paper will be torn so as to cause a parting of the design. In order 30 to reseal the flap, it is necessary to bring it down again over the treated portion *G*, or to recoat the parts to cause their adherence. It is impossible to bring the separated parts 35 of the design into registration, so that by holding the envelope up to the light, one can see, as shown in Figure 2, that the design is not continuous, and hence that the envelope must have been open. In certain instances, in order to facilitate detection, I 40 may use paper which is comparatively thin or transparent.

I desire to call attention to the fact that such a device for detecting the unauthorized opening of the envelope will not apply to 45 the mucilage-sealed envelope, because when such an envelope is opened by steaming it, the design, especially if printed on the paper before the coating is made, will not be torn or broken, but it will be broken with an adhesive, such as I have described.

In shipping these envelopes, I may make use of strips of paraffin paper, or the like, which may be placed between the two adhesive surfaces for preventing the sticking 55 of the same inadvertently. These strips are of course removed when it is desired to seal the envelope which may be done, as stated, by merely pressing the parts together.

I claim:

60 An envelope comprising a body portion having overlapping flaps secured together, a cover flap, said overlapping flaps and said cover flap having roughened registering portions, an adhesive coating insoluble in water 65 carried by the inside edge of the cover flap

and on the outer side of the overlapping flaps on the roughened portions therof, the coated portion of said cover flap being arranged to adhere to the coated portion of said overlapping flaps when the two are 70 pressed together, and a plurality of designs impressed upon the envelope and disposed between the cover flap and the overlapping flaps when said flaps are in their sealed position, said designs being adapted to be 75 torn when said cover flap is raised from said overlapping flaps.

THOMAS E. GJÖRUP.
